UNITED STATES PATENT OFFICE

THOMAS FREDERICK SPACKMAN, OF CHICAGO, ILLINOIS, ASSIGNOR TO STEWART-WARNER CORPORATION, OF CHICAGO, ILLINOIS, A CORPORATION OF VIRGINIA

VACUUM FUEL-FEEDING DEVICE

Application filed July 15, 1929. Serial No. 378,270.

The purpose of this invention is to provide an improved construction for supplying fuel to an internal combustion engine utilizing engine suction for producing vacuum to lift the fuel from the lower source to a receptacle from which it may be delivered to the carburetor. It consists in the elements and features of construction shown and described and as indicated in the claims.

10 In the drawings:—

Figure 1 is a vertical section of an apparatus embodying the invention in one of its forms.

Figure 2 is a similar view of the same in 15 modified form.

In the drawings, in both forms shown, the outer shell forming the reserve chamber is indicated at A; the inner,—upper—vacuum chamber is shown at B, having suction connection, 20, fuel inlet, 21, and fuel discharge to the reserve chamber at 22, controlled by the check valve, C. Referring to the form shown in Figure 1: In the vacuum chamber there is mounted fixedly a cup, D, open at the 20 top nearly at the top of the vacuum chamber, and having bottom outlet ports, 24, 24, arranged to be closed by a float valve device, F, when the latter is buoyed by the liquid in the vacuum chamber rising nearly to the level 25 of the bottom of the cup. In the cup there is a float, F, having stem, F¹, extending out through the bottom of the cup in which the stem has an approximately liquid-tight fit, and extending through a central aperture in 30 the float valve, E, and carrying below said float valve a valve, G, which, at what may be referred to as the normal position of the float, F,—that is, when the cup, D, is emptied of liquid,—is arranged to seat at and close an 35 opening, 26, in the bottom of the vacuum chamber, constituting communication between the vacuum chamber and the fuel reserve chamber, independent of the fuel discharge port which is controlled by the check 40 valve, C. The stem, F¹, is extended down through the opening, 26, and below the same is provided with a stop pin, 27, for limiting the rise of the float, F, in the cup. The 45 reserve chamber has at the top the usual atmosphere vent port, 30.

The operation of this construction may readily be seen to be that, starting with both chambers empty and the vacuum chamber connected with a source of suction and with a source of liquid to be lifted by the suction 55 from a lower level, the valve, C, is held seated by the suction; and when the liquid rises in the vacuum chamber nearly to the level of the bottom of the cup, D, submerging the float valve, E, and the latter is buoyed up 60 against the bottom of the cup and closes the ports, 24, 24; and when the level rises to the top of the cup it will quickly overflow into the latter and fill the limited space therein around the float, causing the float to be 65 buoyed up and lift the valve, G, unclosing the port, 26, and admitting the atmospheric pressure and air which will bubble up through the liquid in the vacuum chamber, venting the 70 vacuum therein and causing the liquid to be discharged therefrom past the valve, C, into the reserve chamber, and lowering the level in the vacuum chamber outside the cup, but not emptying the cup until the level outside 75 the latter has fallen below the level of the bottom of the cup far enough to de-submerge the float valve, E, and permit it to fall so as to uncover the ports, 24, 24; and thereupon the cup will empty and the float will be lowered, carrying the valve, G, down to its seat, 80 closing the port, 26, cutting off the atmospheric pressure; whereupon continuously admitted suction will re-create the vacuum in the vacuum chamber and the cycle of operations will be repeated.

85 Referring to the form shown in Figure 2, it may be noticed that the cup, D, is upheld by a tubular support, D¹, which is connected at a post, 26¹, in the bottom of the vacuum chamber corresponding to the port, 26, of the 90 form shown in Figure 1, and thereby the passage through said tubular support leads directly from the reserve chamber into the cup cavity; and the valve, G, carried by the float stem seats at the upper end of said passage 95 for controlling the port, 26¹, which constitutes the vent connection from the vacuum chamber, by way of the cup cavity, with the reserve chamber through which atmospheric pressure obtains access for venting the 100

vacuum in the vacuum chamber. In this form also the stem of the float and valve, G, extends down into the lower chamber and is provided with a stop, 27*, for limiting the rise of the float. In this form the cup has bottom ports, 24*, corresponding to the ports 24, of the first form, these ports being controlled by a float, E*, corresponding to the float, E, of the first form.

10 The operation of the form shown in Figure 2 is substantially the same as that of the form shown in Figure 1, differing only in that when the cup fills and the float, buoyed by the liquid, lifts the valve, G, opening the 15 vent communication with the lower chamber, the atmospheric pressure obtains access to the vacuum chamber by way of the cup cavity, as above mentioned, the air bubbling up through the liquid in the cup without 20 causing any substantial discharge of the liquid content of the cup until the liquid level in the vacuum chamber falls below the bottom of the cup, and the float, E*, is 25 submerged and falls, opening the ports 24*, and permitting the cup to empty its liquid content into the vacuum chamber from which it discharges past the valve, C, into the reserve chamber.

It will be understood that the reserve chamber, B, may be filled with liquid to the level 30 somewhat above the level of the bottom of the vacuum chamber, the liquid extending up in the annular space around the vacuum chamber, and in such cases the level of the 35 liquid in the reserve chamber must become lowered somewhat before air will reach and enter the vent passage which is controlled by the valve, G; but it will be understood that this will not prevent atmospheric pressure 40 obtaining access by way of the vent passage as described, whether that passage consists only of the port, 26, as in Figure 1, or includes, as in Figure 2, the cavity of the dia- 45 phragm stem and the cavity of the cup, or whether the pressure is transmitted wholly by air or in part by liquid which may be occupying the passage through which the pressure reaches the upper chamber.

And it will be seen, therefore, that the 50 vacuum chamber will discharge its liquid content into the reserve chamber by reason of atmospheric pressure admitted to the vacuum chamber, whether the atmospheric pressure will be transmitted so as to admit only at- 55 mospheric air to the vacuum chamber, or so as to cause some liquid to pass up from the reserve chamber into the vacuum chamber for relieving the vacuum.

I claim:—

60 1. A structure for the purpose indicated comprising in combination with a vacuum chamber and reserve chamber, the vacuum chamber having a port for discharging into the reserve chamber, a valve controlling said port arranged to be opened by the outflow

from the vacuum chamber and to be held seated by suction in said chamber, the vacuum chamber having connection with a source of suction and connection for liquid supply from a lower source from which the same may be lifted by suction in the vacuum chamber, 70 said vacuum chamber having at the lower part a second port of communication with the reserve chamber in addition to said discharge port; an upwardly open cup mounted 75 in the vacuum chamber; a float in the cup and a valve carried by the float controlling the said second port and arranged to be held seated by the weight of the float and to be lifted for opening said port by the buoyant effort of the float when the cup is filled with liquid to a predetermined level; the cup having at the lower part a waste port discharging in the vacuum chamber means in the vacuum chamber controlling said waste port arranged to be operated by change of liquid level in said vacuum chamber to open the waste port when the liquid falls below a predetermined low level and close said port when the liquid rises a very short distance above 90 said low level.

2. In the construction defined in claim 1, the float-carried valve having a stem extending through the port which it controls, and a stop on said stem below said port for limiting the upward movement of the float in the cup.

3. In the construction defined in claim 1, the cup cavity having communication with the reserve chamber independent of its communication with the vacuum chamber, and the valve controlling said communication being carried by the float within the cup.

4. In the construction defined in claim 1, the cup being supported at a short distance above the bottom of the vacuum chamber and having the waste port in the bottom, the waste-port-controlling means being a float valve device interposed between the cup bottom and the bottom of the vacuum chamber.

5. In the construction defined in claim 1, the cup being supported at a short distance above the bottom of the vacuum chamber and having the waste port in the bottom, the waste-port-controlling means being a float valve device interposed below the cup bottom; a tubular member, extending across the vertical interval between the cup bottom and the vacuum chamber bottom affording pressure communication between the reserve chamber and the cup cavity and vacuum chamber, the float valve device being apertured for engaging and being positioned and guided by said tubular member.

In testimony whereof, I have hereunto set my hand at Chicago, Illinois, this 12th day of July, 1929.

THOMAS F. SPACKMAN.
